United States Patent Office

Des. 186,159
Patented Sept. 22, 1959

186,159

TOW TRACTOR

Michael Chucta, Battle Creek, Mich., assignor to Clark
Equipment Company, a corporation of Michigan

Application May 25, 1959, Serial No. 56,050

Term of patent 14 years

(Cl. D14—3)

FIG. 1

The essential features of my design reside in those portions shown in full lines.

I claim:

The ornamental design for a tow tractor, as shown and described.
